DESIGN FOR A GLOVE PROTECTOR

Harvey B. Richards, Lake Bluff, Ill., assignor to Richards, Boggs & King, Inc., Chicago, Ill., a corporation of Illinois

Application February 27, 1937, Serial No. 67,894

Term of patent 7 years

To all whom it may concern:

Be it known that I, Harvey B. Richards, a citizen of the United States, residing at Lake Bluff, in the county of Lake and State of Illinois, have invented a new, original, and ornamental Design for a Glove Protector, of which the following is a specification, reference being had to the accompanying drawing forming a part thereof.

I claim:

The ornamental design for a glove protector substantially as shown.

HARVEY B. RICHARDS.
